11 Claims. (Cl. 104—32)

1

The invention relates to apparatus for removing and replacing the trucks, wheels or other parts of the running gear of railway vehicles and more particularly to apparatus of the type adapted to operate in a pit below the vehicle.

A general object of the invention is to extend the field of usefulness of such apparatus by improvements in construction and organization which particularly adapts it for the repair, servicing or replacement of the trucks or running gear of Diesel locomotives.

Another object is to provide apparatus of the above general character requiring only a relatively shallow drop pit for its accommodation, thereby affording substantial savings in the construction of the pit and reducing equipment costs to a minimum.

A more specific object is to provide a combined drop pit table and pit carriage including built-in elevator mechanism embodied in a simple unitary structure which can be manufactured at relatively low cost.

Still another object is to provide improved mechanism for supporting a vehicle body while the trucks or wheels are being removed and replaced.

A further object is to provide improved controls for coordinating the operation of the drop pit table and the vehicle body supporting mechanism to afford maximum safety in the handling of heavy equipment.

Other objects and advantages of the invention will become apparent from the following detailed description of the preferred embodiment illustrated in the accompanying drawings, in which:

Figure 1 is a fragmentary plan view of a drop pit installation equipped with a drop pit table and vehicle body supporting mechanism embodying the features of the invention.

Fig. 2 is a sectional view taken in a vertical plane substantially on the line 2—2 of Fig. 1, showing details of the vehicle body supporting mechanism.

Fig. 2a is an end view of the body support latch taken in a vertical plane substantially on the line 2a—2a of Fig. 2.

Fig. 3 is a view taken transversely of the drop pit showing the pit table in pit-bridging position.

Fig. 4 is a side elevational view of the pit table in raised or pit-bridging position.

Fig. 5 is a view taken transversely of the drop pit showing the table raised above track level and with the supporting mechanism in operative position.

Fig. 6 is a view similar to Fig. 5 showing the table lowered to drop the trucks of the vehicle.

2

Fig. 7 is a diagram of the electrical and hydraulic circuits of the drop pit apparatus.

Fig. 8 is a diagram of the electrical and hydraulic circuits of the supporting mechanism.

The present invention may be used with various pit and trackage arrangements for servicing a wide variety of railway vehicles. For purposes of illustration, the mechanism has been shown in connection with a drop pit 10 (Figs. 1, 3, 5 and 6) intersecting and extending beneath a service track comprised of rails 11. When intended for servicing certain types of vehicles, such as Diesel locomotives, an inspection pit 12 is usually provided below the service track at opposite sides of the drop pit table. Usually the drop pit 10 is extended across a plurality of service or transfer tracks between which vehicle wheels or trucks may be transferred by elevating and transporting mechanism operating on rails 13 extending longitudinally of the drop pit and forming a pit track.

In accordance with one aspect of the invention the elevating and transporting mechanism is constructed as a simple, self-contained unit or combined drop pit table and pit carriage 15 particularly adapted for operation in a relatively shallow pit. Considerable saving in initial construction costs is thus afforded as compared with deep pit installations required with conventional drop pit apparatus. Furthermore, construction of the apparatus is simplified, enabling it to be manufactured at lower cost and to be maintained economically.

Referring more particularly to Figs. 1, 3 and 4 of the drawings, the apparatus unit 15, which may be conveniently termed a drop pit table, comprises a rigid generally rectangular table structure 16 built up of heavy I-beams or other structural shapes sufficiently strong and rugged to support the weight of a heavy railway vehicle such as a Diesel locomotive. The table structure 16 is dimensioned so as to span the drop pit transversely and is arranged for movement vertically and longitudinally within the pit. Rails 17 on the upper face of the table structure form an extension track adapted to bridge the gap in the service track 11 when the table structure occupies the pit-bridging position in which it is shown in Fig. 3. Flanged wheels 18 are provided on the table structure for supporting it on the pit track 13 when lowered to transport position. Preferably the top of the table structure is floored between and on opposite sides of the rail 17 by metal plates 19 and 19a which are located flush with the shop floor when the table structure is supported at the position shown in Fig. 3.

To insure adequate stability when a locomotive is run over the pit, the drop pit table 15 is releasably supported in pit-bridging position by latches 20 engageable with suitable ledges 21 on the side walls of the pit 10. Where an inspection pit 12 is installed, the ledges 21 are conveniently formed on or carried by upright members 22 disposed at opposite sides of the inspection pit.

The latches 20 as herein shown comprise heavy metal bars mounted in suitable guides formed in the table structure for endwise movement from the projected or active position in which they are shown in Fig. 3 to an inactive or withdrawn position as shown in Figs. 5 and 6 in which they are retracted to clear the ledges 21.

While projection and retraction of the latches may be effected by any suitable means, it is preferred to employ a power-operated actuator 23 for that purpose. The actuator 23 as herein shown is of the pressure fluid operated type adapted to receive pressure fluid from a suitable source and under control of valve means described in detail hereinafter. In its preferred form, the power-operated actuator comprises a cylinder 23' (Figs. 3 and 7) having a working piston 24 connected by a piston rod 25 and linkage with the latches 20, of which there are four in the exemplary drop pit table. The linkage includes a rockshaft 26 extending across the table structure and having suitably positioned oppositely directed radial arms 27 connected by links 28 with the respective latches. The arrangement is such that the latches may be projected or retracted simultaneously by appropriate rocking of the shaft 26. Such rocking is effected through the medium of a crank arm on the shaft operatively connected with the piston rod 25.

As indicated above, the drop pit table 15 is provided with built-in elevator mechanism for raising and lowering the table structure in the pit 10. This mechanism, while capable of lifting the table structure from its transport position on the pit track 13, as shown in Fig. 6, to a position several inches above the level of the service track 11, as shown in Fig. 5, is characterized by its simplicity and ruggedness, and more particularly by its compactness which is an important consideration in reducing the pit depth required for the accommodation of the apparatus. This factor, together with the construction of the table for service as a pit carriage, permits the apparatus to function efficiently in a pit of minimum depth.

Referring now to Figs. 1, 3, 4 and 7 of the drawings, the elevator mechanism is of the pressure fluid operated type comprising a plurality of fluid operated actuators 30 mounted on the table structure 16 and adapted to exert a thrust against the pit floor to raise the table from the pit track 13. The actuators 30 are preferably of the cylinder and piston type, each comprising a cylinder 31 with a working piston 32 (Fig. 7) having a piston rod 33 projecting from one end of the cylinder.

Four of the cylinder and piston actuators 30 are provided in the exemplary pit table. These actuators are arranged in pairs on opposite sides of the table structure and in vertical alignment with the rails 13 of the pit track. For this purpose each of the cylinders 31 has at one side a flat mounting plate 34 (Figs. 1, 3 and 4) adapted to be secured to the table structure 16 as by bolts 35. The cylinders are mounted in upright positions with the piston rods 33 projecting downwardly. Preferably each piston rod is provided at its lower end with a channel-shaped shoe 36

adapted to engage and rest on the rail 13. Accordingly upon introduction of pressure fluid in the upper ends of the cylinders 31, pistons 32 and their piston rods 33 are shifted downwardly until shoes 36 engage rails 13. Thereafter the cylinders 31 are shifted upwardly relative to the piston rods and the entire table structure is raised.

To cushion the shock at the upper ends of the stroke, each of the cylinders 31 is formed at its lower end with a recess 37 (Fig. 7) of reduced diameter for the reception of a collar-like enlargement 38 on the piston rod 33 adjacent the piston 32. The recess and piston rod enlargement are dimensioned so as to restrict the exhaust of fluid from the cylinder and thus slow down the rate of movement as the cylinder approaches the piston. The pit table may therefore be brought to rest with a minimum of shock.

Power means is also provided for traversing the pit table 15 along the pit track 13. This power means may conveniently comprise a reversible rotary pressure fluid operated motor TM (Figs. 1, 3 and 7). As shown in Fig. 1 the motor TM is mounted on the table structure 16 intermediate one pair of wheels 19 and is drivingly connected by speed reduction gearing G with a shaft 41 extending across the table. The shaft 41 is drivingly connected with the wheels by a pinion 42 coaxing with gears 43 rigid with the wheels.

In accordance with another aspect of the invention, the latch bar actuator 23, the elevator actuators 30 and the table driving motor TM are organized in a unitary hydraulic system and are supplied with pressure from a common source such as a pump P (Figs. 1 and 7) driven by an electric motor M. As the pump and motor, along with other elements of the hydraulic system, are mounted on the traveling pit table, electric current for operating the motor and the controls associated with the system is supplied through a flexible cable 44 (Fig. 4) adapted to be reeled in and paid out by a spring-actuated cable reel 45 which may be supported on the table structure or located at one end of the pit 10, as preferred. As shown in Fig. 1 a trap door is provided in the central floor plate 19 to provide access to the motor M and pump P for adjustment or repair.

Referring to Fig. 7 of the drawings, pump P draws fluid such as oil from a sump or reservoir R and delivers it under pressure to a fluid supply conduit 47 by way of a pressure responsive relief valve RV. One branch 48 of the supply conduit extends to a reversing valve V-1 operated in one position to direct pressure fluid through a conduit 49 and check valve CV and flow equalizer E to the upper ends of the actuator cylinders 31. The flow equalizer E may be of any of the several well-known types in general use and provides a uniform flow of fluid to each actuator cylinder under all load conditions, thereby insuring movement of the actuators in step and maintaining the table structure level at all times.

In its other position the valve V-1 directs pressure fluid by way of a conduit 51, check valve CV-1 and flow equalizer E-1 to the lower ends of the cylinders 31. The conduits 49 and 51 are connected alternately with a drain conduit 52 in the respective positions of the valve V-1.

The particular reversing valve shown in the exemplary hydraulic system is spring-biased to a central position in which both conduits 49 and 51 are blocked. Fluid is thus trapped in the cylinders 31 and movement of the pistons in either direction is effectively prevented when the reversing valve is in neutral position. Movement of

the valve V-1 to the position for raising the table structure is effected by a solenoid SOL-1 energized upon closure of a manually operable "raise" switch RS.

Since the reversing valve is biased to central or neutral position, the lifting action continues only as long as the switch RS is held closed. The lifting can thus be interrupted at any point by simply releasing the switch. Provision is also made for returning the reversing valve to neutral position regardless of whether or not the control switch is released when the table structure reaches its upper limit position. This means as shown comprises a normally closed limit switch S-1 connected between the switch RS and the solenoid SOL-1 and adapted to be opened by a cam 53 on one of the cylinders 31.

Shifting of the reversing valve V-1 to its alternate or lowering position is effected by a solenoid SOL-2. The energizing circuit for the latter solenoid includes a normally open manually operable switch LS and a limit switch S-2 operable by a cam 54 on one of the rail engaging shoes 36 which limit switch is normally closed when the elevator mechanism is supporting the table structure on the rails 13, and an interlocking safety switch SS-1 (Fig. 8) associated with the vehicle body supporting mechanism. The arrangement is such that the operation of that mechanism and the hoist is always properly coordinated, as explained hereinafter. Assuming that the limit and safety switches are closed, the lowering action of the elevator mechanism continues only while the switch LS is held closed and is interrupted when the switch is released. Initially, of course, the cylinders 31 descend with reference to their pistons 32 until the wheels 18 of the table structure engage the rails 13. Thereafter, the pistons 32 are shifted to the upper ends of their associated cylinders and thus raise the shoes 36 from the rails 13 so that the pit table may be traversed thereon without interference.

The equalizers E and E-1 in the fluid supply circuits for the actuators 30 insure operation of the actuators at the same rate and thus maintain the table structure level under all operating conditions. Control of the raising or lowering speeds is effected by metering the exhaust from the respective actuator cylinders. For this purpose, adjustable metering valves MV and MV-1 are connected in parallel relation respectively with the check valves CV and CV-1. The arrangement is such that fluid flow toward the actuators passes freely through the check valves while flow from the actuators is diverted through the metering valves.

Pressure fluid for operating the latch bar actuator 23 is supplied through a second branch conduit 55 and under control of a reversing valve V-3. This valve, which may be operated manually by means of a hand lever 56, connects the opposite ends of the actuator cylinder 23 alternately with the branch conduit 55 and the drain conduit 52.

A third branch conduit 57 supplies pressure fluid to the traverse motor TM under control of a reversing valve V-4 which determines the direction of rotation of the motor and therefore the direction of travel of the table 15. This valve is normally spring-biased to a central or neutral position in which both ports leading to the motor are blocked. A solenoid SOL-4 energized upon closure of a normally open manually operable "forward" switch FS shifts the valve to a position to effect a forward movement of the pit table.

Shifting of the valve V-4 to its alternate position, thereby reversing the direction of movement of the table, is effected by a solenoid SOL-5 energized upon closure of a normally open manually operable "reverse" switch RS-1. An adjustable metering valve MV-2 may be interposed in the branch conduit 57 for regulating the speed of the traverse motor TM.

Means is provided for instantly unloading the 10 hydraulic system in the case of an emergency. This means includes a valve V-5 interposed in a branch conduit 58 leading from the relief valve RV to the drain 52. Valve V-5 is spring-biased to an open position but when the system is in 15 operation, it is held closed by a solenoid SOL-6 energized in a circuit including a normally closed manually operable "stop" switch SS. Thus, upon power failure or in response to the actuation of the "stop" switch, solenoid SOL-6 is 20 deenergized and valve V-5 opens to divert all pressure fluid from the pump, thereby immediately interrupting any function of the pit table that may be in progress.

The electrical controls above described are 25 preferably arranged for low voltage operation and may be supplied with current from the motor supply circuit through a suitable step-down transformer 59. A suitable contactor or control switch (not shown) is provided in the motor circuit for starting and stopping the motor. The various manually operable switches are desirably of the push-button type and for convenience of operation may be mounted on a portable hand set connected with the solenoids and other elements of the system by a flexible conductor cable.

Associated with and forming a part of the drop pit apparatus above described is a novel mechanism providing support for the body of a vehicle while a set of wheels or truck is removed therefrom with the assistance of the pit table 15. The supporting mechanism in its preferred form comprises a column 60 (Figs. 2, 5, 6 and 8) supported between the rails of the service track 11 in a rigid frame 61 carried by the uprights 22 at the sides of the inspection pit and at one side of the drop pit 10. The column 60 is slidable vertically in the frame from the extended position in which it is shown in Figs. 2 and 8 to a retracted position in which its top portion is approximately at or below the level of the service track as shown in Fig. 1 so that the vehicle may be run over it without interference.

As shown in Fig. 2, the column 60 is in the form of a hollow cylinder with an auxiliary jack screw 55 62 threaded into its upper end. The jack screw is provided with a flat head element 64 for engaging the pad which is ordinarily provided on the vehicle body for jacking purposes. By screwing the jack in or out, the effective length of the support may be adjusted to conform to variations in the spacing of the jacking pad with respect to the track level.

Movement of the column 60 between extended and retracted positions is effected by a pressure fluid operated actuator comprising, in this instance, a cylinder 65 supported in an upright position on a cross beam 66 extending transversely of the inspection pit. The cylinder is fitted with a piston 67 (Fig. 8) having a piston rod 68 extending upwardly into the column and operatively connected with it by means of a cross pin 69. Accordingly, when fluid under pressure is admitted to the lower end of the cylinder 65, the 70 column is raised to extended position. When the 75

cylinder is vented, the column returns to retracted position by gravity.

Due to the relatively heavy loads imposed on the column 60 and to the necessity of maintaining it in position to support a load irrespective of power failures or the like, means is provided for positively locking it in the extended position independently of the pressure fluid operated actuator. Since this locking means is arranged to sustain the load on the column mechanically independently of the actuator, the latter may be of relatively light and inexpensive construction. Such positive locking of the column provides maximum safety in the operation of the pit apparatus as it effectually prevents accidental lowering of a vehicle into the open pit in which men may be working.

The column locking means in its preferred form comprises a locking bar 70 supported at opposite sides by guide bars 71 (Figs. 2 and 2a) on the frame 61 so that it may slide under the column when the latter is raised to its extended position. Accordingly, when a load is imposed on the column it is transmitted through the locking bar to the frame 61 independently of the pressure fluid actuator. As will be seen by reference to the drawing, the locking bar 70 is formed with a longitudinal slot 72 providing clearance for the cylinder 65 when the bar is advanced to operated or locking position.

Movement of the bar 70 between locking and release positions is effected by power-actuated means, herein shown as a pressure fluid operated actuator comprising a cylinder 73 having a working piston 74 (Fig. 8) connected by a piston rod 75 with the locking bar. The cylinder is disposed in a substantially horizontal position and in the present instance is anchored at its closed end to one of the uprights 22 as by a pin 76.

Operation of the column and latch actuators in proper timed relation is insured by the novel electrical and hydraulic system in which those actuators are incorporated. Pressure fluid is supplied to the system by a pump P-1 driven by an electric motor M-1. The pump draws fluid, such as oil, from a sump or reservoir R-1 and delivers it under pressure to a supply conduit 77 equipped with the usual relief valve RV-1. A branch 78 of the conduit 77 extends to a conventional two-position reversing valve V-6 operative to connect the lower end of the cylinder 65 alternatively with the supply conduit or with a drain conduit 79. Pressure fluid flows from the valve to the cylinder by way of a check valve CV-1 while fluid exhausted from the cylinder returns to the reversing valve by way of a metering valve MV-3 connected in parallel with the check valve. The metering valve is preferably adjustable to provide for regulating the speed of retraction of the column 60.

The reversing valve V-6 is shifted to its alternate positions by means of solenoids SOL-7 and SOL-8. Solenoid SOL-7 is energized upon closure of a normally open manually operable "raise" switch RS-2 to initiate the raising of the column 60. The circuit of the solenoid SOL-8 is controlled by the latch bar 70 through the medium of a limit switch S-3 closed by a cam 79a on the bar when the latter is fully retracted. The circuit for the solenoid SOL-8 also includes a set of normally closed contacts RS-2a associated with the "raise" switch to insure deenergization of the solenoid when the valve is to be shifted to its alternate position. Preferably, the solenoids and control switches are operated in a low voltage circuit herein shown as receiving its

current supply from the main circuit by way of a transformer 59a. Motor M-1 operates in the main circuit which is controlled by the usual switches or contactors (not shown).

5 A second branch 80 of the supply conduit 77 extends to a conventional two-position reversing valve V-7 from which conduits 81 and 82 extend respectively to opposite ends of the latch actuator cylinder 73. The valve may thus be shifted to direct fluid into either end of the cylinder 73 while venting the other end to the drain conduit 79. Such shifting is effected by means of solenoids SOL-9 and SOL-10. Solenoid SOL-9 is energized by closure of a limit switch S-4 upon movement of the column 60 to its extended position. Such actuation of the switch is effected in this instance by a cam 83 carried by the column. Thus the full extension of the column initiates the shifting of the latch bar 70 into supporting relation to the column.

With withdrawal of the latch bar 70 and retraction of the column 60 is initiated by closure of a normally open manually operable "lower" switch LS-1 which completes an energizing circuit for the solenoid SOL-10. Associated with the "lower" switch is a normally closed switch LS-1a which opens the circuit of the solenoid SOL-9 to enable the companion solenoid to shift the valve to its alternate position. Upon full retraction of 20 the latch bar 70, switch S-3 is closed to energize the solenoid SOL-8 and initiate the lowering of the column.

35 In an emergency, the hydraulic system may be unloaded by operation of a stop switch SS-2 to deenergize a solenoid SOL-11 which normally holds a stop valve V-7 in closed position. When the solenoid is deenergized, the valve is opened by a spring and diverts all pressure fluid from the pump P-1 to the sump by way of a drain conduit 79b.

40 Reference has been made heretofore to the interlocking of the drop pit table elevator controls with the controls for the vehicle body supporting mechanism. For this purpose conductors 85 and 86 from the limit switch S-2 and the solenoid SOL-2 of the elevator controls are carried through the transmission cable 44 and connected by way of contact rings 87 and 88 of the cable reel 45 with conductors 89 and 90 leading to the safety switch SS-1. This switch is supported in a position such that it is closed by the latch bar 70 upon movement of the latter to operated or latching position. A cam 91 on the supporting column 60 is also arranged to close the safety switch when the column is in its lowered or retracted position.

45 With the above arrangement, the lowering of the vehicle body onto the supporting column while the column is being raised or before it is securely latched in operating position is effectively prevented. However, normal operation of the elevator mechanism is permitted when the column is fully retracted.

50 In the operation of the improved drop pit apparatus, the table structure 15 is latched in pit bridging position, as shown in Fig. 3, and the vehicle is run over the pit with the truck to be removed spotted on the table. The "raise" switch RS is then closed, initiating the operation of the actuators 30 to raise the table above pit level, as shown in Fig. 5, thus removing the load from the latch bars 20. The latch bars may then be retracted by operation of the valve V-3.

55 While the elevator table is in its uppermost position, the supporting column 60 is extended

by closure of the "raise" switch RS-2. When the column reaches its fully extended position closure of limit switch S-4 initiates operation of the latch actuator mechanism to shift the latch bar 70 into supporting relation to the column. In practice the column is usually so constructed that it does not reach the jacking pad of the vehicle and accordingly the screw jack 62 is turned up until the head 64 engages the jacking pad.

After the trucks are detached from the vehicle they may be lowered into the pit for transportation to another service or transfer track. Such lowering is initiated by operation of the "lower" switch LS. As the table structure descends into the pit the weight of the vehicle body is transferred onto the column 60 and through the latch bar 70 to the supporting framework in the pit.

To replace the wheels or truck, the above sequence of operations is reversed. The table is run under the vehicle and elevated to the position shown in Fig. 5. This relieves the column 60 of the load so that the latch bar 70 may be withdrawn and the column retracted upon closure of the "lower" switch LS-1. The table is now lowered to the pit-bridging position and the latches 20 operated to latch the table in position.

It will be apparent from the foregoing that the invention provides drop pit apparatus of novel and advantageous construction. The improved apparatus is particularly well adapted for the repair, servicing or replacement of the running gear of Diesel locomotives. By reason of its novel construction, only a relatively shallow pit is required, thus affording substantial savings in the cost of constructing the pit and reducing equipment costs to a minimum.

The vehicle body supporting means is characterized by the ease with which it may be conditioned for operation or retracted to an out of the way position when not required. A novel interlocking arrangement between the pit elevator mechanism and the supporting mechanism effectively coordinates their actions for safe operation.

I claim as my invention:

1. Apparatus for use in a pit intersecting and extending beneath a service track and having rails providing a pit track extending transversely of the service track, said apparatus comprising, in combination, a rigid table structure dimensioned to fit within the pit and movable vertically therein, said table structure having means for carrying a track section, retractable latch members on said table structure engageable with the pit walls for supporting the table structure adjacent the top of the pit with the track section thereon bridging the gap in the service track, a plurality of wheels on said table structure engageable with the rails of the pit track and operative to support the table structure thereon substantially below the top of the pit, elevator mechanism mounted on said table structure for shifting it between said two supported positions, said mechanism including a pair of vertically disposed cylinders mounted at each end of said table structure substantially in alignment with the rails of the pit track, a piston working in each cylinder and having a downwardly extending piston rod terminating in a rail engaging shoe, a source of fluid under pressure, and valve means operable to control the flow of pressure fluid to and from said cylinder to effect the lifting or lowering of said table structure.

2. Apparatus for use in a pit intersecting and

extending beneath a service track and having rails providing a pit track extending transversely of the service track, said apparatus comprising, in combination, a rigid table structure dimensioned to fit within the pit and movable vertically therein, retractable latch members on said table structure engageable with the pit walls for supporting the table structure adjacent the top of the pit, said table structure having means for carrying a track section operable to bridge the gap in the service track when the table structure is latched to the pit, a plurality of wheels on said table structure engageable with the rails of the pit track and operative to support the table structure thereon substantially below the top of the pit, elevator mechanism mounted on said table structure for shifting it between said two supported positions, said mechanism including a pair of vertically disposed cylinders mounted at each end of said table structure substantially in alignment with the rails of the pit track, a piston working in each cylinder and having a downwardly extending piston rod terminating in a rail engaging shoe, a source of fluid under pressure, a reversing valve operable to direct fluid from said source to the opposite ends of said cylinders alternately, and manually operable control means for selectively operating said reversing valve.

3. Apparatus for use in a pit intersecting and extending beneath a service track and having rails providing a pit track extending transversely of the service track, said apparatus comprising, in combination, a rigid table structure having wheels adapted to travel on the pit track, said table structure having means for carrying a section of track, elevator mechanism operative to raise said table structure from the pit track to a position adjacent the top of the pit with the track section thereon bridging the gap in the service track, said elevator mechanism including a plurality of pressure fluid operated actuators carried by the table structure and cooperating with the rails of the pit track, a fluid motor operative to drive said table structure along the pit track, a source of fluid under pressure, independently operable reversing valves for respectively controlling the flow of fluid from said source to said actuators and said motor, and a stop valve operable to interrupt the flow of pressure fluid to said actuators and said motor independently of said reversing valves.

4. Drop pit apparatus for servicing the wheels and trucks of railway vehicles comprising, in combination, a table structure dimensioned to operate in a pit intersecting and extending beneath a service track, said table structure having means for carrying a track section operative to extend the service track across the pit, elevator mechanism associated with said table structure operative to raise and lower the table structure, means for supporting the body of a vehicle when a set of wheels or truck is removed therefrom by lowering the elevator, said supporting means comprising a member movable vertically from a retracted position below the service track into engagement with the underside of the vehicle body, power operated means for moving said member, a latch element shiftable into a position to mechanically retain said member in its raised position and to support the load imposed on the member, and control means operable by said latch element for preventing operating of said eleva-

tor mechanism to lower said table structure until the latch element has been shifted into latching position.

5. Drop pit apparatus for servicing the wheels and trucks of railway vehicles comprising, in combination, a table structure dimensioned to operate in a pit intersecting and extending beneath a service track, said table structure having means for carrying a track section adapted to extend the service track across the pit, elevator mechanism associated with said table structure operative to raise and lower the table structure, means for supporting the body of a vehicle when a set of wheels or truck is removed therefrom by lowering the elevator, said supporting means comprising a member movable vertically from a retracted position below the service track into engagement with the underside of the vehicle body, power operated means for moving said member, a latch element shiftable into a position to mechanically retain said member in its raised position and to support the load imposed on the member, control devices for said elevator mechanism operable selectively to initiate the raising or lowering of the table structure, and an auxiliary control device actuated in accordance with the position of said latch element to render effective or ineffective the device for initiating the lowering of the table structure.

6. Drop pit apparatus for servicing the wheels and trucks of railway vehicles comprising, in combination, a table structure dimensioned to operate in a pit intersecting and extending beneath a service track, said table structure being adapted to carry a track section for extending the service track across the pit, elevator mechanism associated with said table structure operative to raise and lower the table structure, means for supporting the body of a vehicle when a set of wheels or truck is removed therefrom by lowering the elevator, said supporting means comprising a member movable vertically from a retracted position below the service track into engagement with the underside of the vehicle body, power operated means for moving said member, a latch element shiftable into a position to mechanically retain said member in its raised position and to support the load imposed on the member, a control system for said elevator mechanism including an electrical circuit operative when closed to initiate a downward movement of the mechanism, a normally open safety switch in said circuit closed upon movement of said latch element into latching position.

7. Drop pit apparatus for servicing the wheels and trucks of railway vehicles comprising, in combination, a table structure dimensioned to operate in a pit intersecting and extending beneath a service track, said table structure being adapted to carry a track section for extending the service track across the pit, elevator mechanism associated with said table structure operative to raise and lower the table structure, means for supporting the body of a vehicle when a set of wheels or truck is removed therefrom by lowering the elevator, said supporting means comprising a member movable vertically from a retracted position below the service track into engagement with the underside of the vehicle body, power operated means for moving said member, a latch element shiftable into a position to mechanically retain said member in its raised position and to support the load imposed on the member, a control system for said ele-

vator mechanism including an electrical circuit operative when closed to initiate a downward movement of the mechanism, a normally open manually operable switch in said circuit, a second switch in said circuit closed when the table structure is in a raised position, and a third switch in said circuit closed incident to the movement of said latch element to latching position.

8. Drop pit apparatus for servicing railway vehicles comprising, in combination, a table structure dimensioned to operate in a pit intersecting and extending beneath a service track, said table structure having means for supporting a track section operative to extend the service track across the pit, elevator mechanism associated with said table structure operative to raise and lower the same, means for supporting the body of a vehicle spotted over the pit when a set of wheels or truck is removed therefrom by lowering the elevator mechanism, said supporting means comprising a member supported between the rails of the service track at one side of the pit for movement vertically from a retracted position at or below the level of the service track to a raised position in engagement with the underside of the vehicle body, power operated means for moving said supporting member to raised position, a rigid element shiftable into a position to mechanically retain said member in raised position and to support the load imposed on the member, other power operated means for shifting said element to and from supporting position, and controls governing the operating sequence of said two power operated means.

9. Drop pit apparatus for servicing railway vehicles comprising, in combination, a table structure dimensioned to operate in a pit intersecting and extending beneath a service track, said table structure having means for supporting a track section operative to extend the service track across the pit, elevator mechanism associated with said table structure operative to raise and lower the same, means for supporting the body of a vehicle spotted over the pit when a set of wheels or truck is removed therefrom by lowering the elevator mechanism, said supporting means comprising a member supported between the rails of the service track at one side of the pit for movement vertically from a retracted position at or below the level of the service track to a raised position in engagement with the underside of the vehicle body, power operated means for moving said supporting member to raised position, latch means operative to retain said supporting mechanism in raised position, control devices for said elevator mechanism operable selectively to initiate the raising or lowering of the table structure, and an auxiliary control device actuated by said latch means cooperating with the control device for initiating the lowering of the table structure to control the operation of said elevator mechanism.

10. Vehicle body supporting mechanism comprising, in combination, a supporting member mounted between the rails of a service track for movement from a position substantially at or below track level to a raised position in engagement with the underside of the body of a vehicle standing on the track, a power-operated actuator for raising and lowering said supporting member, a latch element shiftable transversely of said supporting member into or out of latching engagement therewith, a power-operated actuator for shifting said latch element, control

means operative upon the movement of said supporting member to its raised position for initiating the operation of the latch element actuator to shift the element into latching engagement with the member, manually operable means for initiating the operation of said latch element actuator to withdraw the element from latching engagement with the member, and control means rendered effective incident to the withdrawal of the latch element for initiating the operation of said first-mentioned actuator for lowering said supporting member to retracted position.

11. Vehicle body supporting mechanism comprising, in combination, a supporting member mounted between the rails of a service track for movement from a position substantially at or below track level to a raised position in engagement with the underside of the body of a vehicle standing on the track, a power-operated actuator for raising and lowering said support-

ing member, a latch element shiftable transversely of said supporting member into or out of latching engagement therewith, a power-operated actuator for shifting said latch element, and control means operated upon the movement of said supporting member to its raised position for initiating the operation of the latch element actuator to shift the element into latching engagement with the member.
